REFRIGERATOR CABINET

Filed Sept. 9, 1927

UNITED STATES PATENT OFFICE

HARVEY D. GEYER, OF DAYTON, OHIO, ASSIGNOR TO THE INLAND MANUFACTURING COMPANY, OF DAYTON, OHIO, A CORPORATION OF DELAWARE

REFRIGERATOR CABINET

Application filed September 9, 1927. Serial No. 218,554.

This invention relates to refrigerator cabinets or similar heat insulated cabinets.

The general object of the invention is to provide such cabinets from separate panels molded to shape from a plastic material and assembled together to give in effect a one piece molded cabinet which is well appearing, strong, efficient as a heat insulator, and economical to manufacture.

10 A more specific object is to provide such a cabinet wherein the molded panels are so shaped as to contact with the inner metal lining at relatively small areas and so provide a jacket chamber between the panels and the 15 sides of the metal lining to receive the heat insulating material.

Another object is to provide for filling the 20 jacket chambers in the vertical panels with loose heat insulating material through openings exposed when the bottom panel is removed, thereby greatly simplifying and reducing the cost of building the cabinet.

Another object is to provide a cabinet having a vertical door hinged directly to a 25 thickened portion of one of the side panels and abutting the adjacent thickened portions of the other panels. It is thus provided that the door forms the entire front of the cabinet and no door-opening frame is required other 30 than the above mentioned thickened portions integral with the side, top, and bottom panels. The entire cabinet is therefore formed from six molded panels including the door panel.

Another object is to provide an improved 35 molded panel door construction having an inner metal lining and a soft rubber sealing jacket, and an inner ring of molded plastic material overlapping and concealing the edges of said lining and also serving to retain 40 the gasket in place.

Further objects and advantages of the present invention will be apparent from the following description, reference being had to the accompanying drawing, wherein a preferred form of embodiment of the present 45 invention is clearly shown.

In the drawing:

Fig. 1 is a vertical section of a refrigerator cabinet built according to this invention and 50 is taken on line 1—1 of Fig. 2.

Fig. 2 is a horizontal section through the cabinet taken on line 2—2 of Fig. 1.

Fig. 3 is a plan view of the inverted cabinet with the bottom panel and door removed, and illustrates how the vertical jacket chambers may be filled with loose cork or other 55 insulating material through the openings thereto exposed by the removal of the bottom panel.

Fig. 4 is a vertical elevation of the inner 60 side of the cabinet door.

Similar reference characters refer to similar parts throughout the several views.

Numeral 10 designates the inner sheet metal lining built in box form with one open side 65 forming the doorway. This lining 10 has all its seams soldered or welded to form in effect a one piece lining. All the cabinet panels are separately molded to the form clearly 70 illustrated from a bituminous plastic material such as, or similar to, that described in my copending application, Serial No. 169,669, filed February 19, 1927. This material is especially well adapted for this purpose since 75 it is non-rusting, moisture proof, a good non-conductor of heat, readily receives and grips small nails and screws without splitting or breaking, and can be economically molded into the shapes of the parts illustrated in the drawings.

The panels all have thickened marginal 80 portions to provide for strong joints therebetween and also for increasing the strength and rigidity of the box structure as a whole. The two side panels 11, the back panel 12, and the top panel 13 are rigidly joined along their contacting edges by a 45 degree miter joint 15 and the small diagonally disposed 85 stove bolts 16 which are suitably spaced apart along the joint to tightly clamp the two contacting mitered edges together. The heads and nuts of the bolts 16 are countersunk into the material and are after assembly completely concealed by the sealing plugs 17 composed of a suitable plastic sealing material, preferably of a bituminous compound similar to 90 that from which the panels are molded. The corner cracks 20 are completely sealed off and obliterated from the outside by fusing together the material of the panels by means 95

100

of a hot metal form pressed firmly up against the corners. The joints of the cabinet are thus completely sealed against moisture entering the insulating material and causing deterioration thereof, and the cabinet has the appearance of being molded all in one piece.

The thickened bottom edges of the vertical panels 11 and 12 are formed as clearly shown in Figs. 1 and 3. These bottom edges have at each end thereof shoulders 31 upon which the flanges 32 of the molded bottom panel 30 seats. This bottom panel 30 is fixed in place by the long screws 33 which extend through the flanges 32 and up into the shoulders 31. The screw holes 34 for screws 33 are shown in Fig. 3. Openings 35 are provided in the bottom edges of the vertical panels leading into the jacket chambers 36 which are filled with the heat insulating material. These openings 35 are of the same width and aligned with the shoulders 31 and hence are completely closed by the flanges 32 when the bottom panel 30 is in place. These openings 35 serve as apertures through which loose ground cork or other heat insulating material may be inserted to fill the jacket chambers 36 when the cabinet is in inverted position, as shown in Fig. 3, and before the bottom panel 30 has been assembled in place.

The bottom panel 30 has a jacket chamber 40 molded therein which is filled with the loose ground cork insulating material, after which the sheet metal cork retaining plate 41 is nailed in place by the small nails 42. It will now be clear that the bottom panel 30, made as above described, can be inverted and set upon the shoulders 31, when the cabinet is in the inverted position as shown in Fig. 3, and fixed in place by the screws 33. If desired, the cracks 45 may be fused together and sealed as described above for the cracks 20, however this is not necessary for good appearance since these cracks 45 are on the bottom surface of the cabinet and hence will not show.

The molded cabinet and metal lining 10 may be assembled as follows: The top panel 13 is first laid in inverted position on the floor and the jacket chamber 37 therein filled with loose ground cork. Next the metal lining 10 (also inverted) is set in its proper place upon the top panel 13 and fixed in place thereupon by the small nails 38. The two side panels 11 and back panel 12 are next assembled in place and fixed to each other and to the top panel 13 by the bolts 16. The vertical jacket chambers 36 are then filled with the loose cork through the openings 35 as described above, after which the bottom panel 30, with its cork and retaining plate 41 in place, is laid upon the shoulders 31 and fixed in place by the screws 33. The edges of the metal lining 10 at the open door-way are tacked down all around by

small nails 38. The cabinet may then be turned up to its normal position and the completed door properly hung in place.

The door panel 50 forms the entire front of the cabinet and is hinged directly to the thickened front edge 51 of one side panel 11 by means of the hinge 52 and the screws 53 which are driven directly into the molded material of the panel. The peripheral flange 55 of the door panel overlaps the thickened front edges 51 of the top, bottom, and two side panels and thus these thickened forward edges 51 serve as a rigid door-opening frame.

The panel 50 has the inwardly projecting marginal flange 56 which forms a jacket chamber 57 for receiving the heat insulating material (preferably loose ground cork). An inner enameled metal lining 58 rests upon the outer edge of the marginal flange 56 and is retained in place by the ring 60 which is molded to shape from the plastic material to telescope upon the slightly tapered outer periphery of the flange 56. This molded ring 60 is secured in place by small screws or nails as clearly shown in Fig. 1. This ring 60 extends adjacent to but stops short of the flange 55 to provide a gasket groove 61 between these two parts, as clearly illustrated. The soft rubber gasket 62 has a portion projecting within groove 61 whereby the gasket is retained in place. The soft rubber gasket 62 may be easily inserted within the groove, or removed therefrom for purposes of renewing the same, simply by stretching a portion of its length at a time to reduce its cross section and then snapping it into the groove while so stretched. This gasket 62 abuts against the inner corners of the door-opening when the door is shut and so seals the joint between the door and door-opening. This door presents a very neat appearance from the inner side since the peripheral edges of the enameled lining 58 are concealed by the ring 60, and no metal parts other than the enameled surface of lining 58 are exposed. Economy of manufacture is materially increased by the non-necessity of forming the lining 58 to any shape other than a plane.

While the form of embodiment of the present invention as herein disclosed, constitutes a preferred form, it is to be understood that other forms might be adopted, all coming within the scope of the claims which follow.

What is claimed is as follows:

1. A refrigerator cabinet comprising: a one-piece inner metal lining having an open side for the door-way, separate panels molded to shape from plastic material enclosing said lining and forming a cabinet therefor, said panels having inwardly projecting marginal portions abutting the corners of said lining and leaving a jacket chamber between 125

the panel and lining, and heat insulating material filling said jacket chambers.

2. A refrigerator cabinet comprising: a plurality of separate panels each having inturned marginal flanges and molded to shape from a plastic material said panels being joined together with said marginal flanges in abutting relationship to form a box structure having an open vertical side for a door-way, a one-piece inner metal lining supported by the marginal flanges of said panels within said box structure but spaced from said panels except at the relatively small supporting areas thereby providing jacket chambers between said lining and the panels, and insulating material filling said jacket chambers.

3. A refrigerator cabinet comprising: separate panels each having inturned marginal flanges and molded to shape from a plastic material, said panels being joined together to form a box structure having an open vertical side for a door-way, a one-piece inner metal lining supported by the marginal flanges of said panels within said box structure but spaced from said panels except at the relatively small supporting areas thereby providing jacket chambers between said lining and the panels, and insulating material filling said jacket chambers, and a heat insulating door for said door-way, said door being hinged directly to the thickened vertical edge of one side panel adjacent said door-way.

35 4. A refrigerator cabinet comprising: separate panels each having inturned marginal flanges and molded to shape from a plastic material said panels being joined together by a miter joint between said marginal flanges to form a box structure having an open vertical side for a door-way, a one-piece inner metal lining supported by said panels within said box structure but spaced from said panels except at the relatively small supporting areas thereby providing jacket chambers between said lining and the panels, and insulating material filling said jacket chambers, and a heat insulating door for said door-way contacting directly with the edges of said molded panels adjacent said door-way, whereby portions of the molded panels serve as a door-opening frame.

5. A refrigerator cabinet comprising: separate side, back, and top and bottom panels molded to shape from a plastic material and rigidly joined directly together at their edges to form a box structure, an inner metal lining supported by said panels at the corner edges thereof but spaced from said panels except at the relatively small supporting areas thereby providing jacket chambers between said lining and said panels, said panels being so shaped that, when the bottom panel is removed from the box structure and lining, openings leading to the vertical jacket

chambers will be provided, whereby said vertical jacket chambers may be filled with loose insulating material through said openings.

6. The steps in the method of making a refrigerator cabinet comprising: forming an inner metal lining for said cabinet, assembling at least three separate exterior vertical panels and one end panel upon said lining to enclose the same, but leaving a jacket chamber between said lining and vertical panels having long narrow openings leading thereto at the other end of said cabinet lining, packing said jacket chambers with heat insulating material through said openings, and then assembling said other end exterior panel upon said lining to overlap the end edges of said vertical panels and cover all of said openings and the end wall of said lining.

In testimony whereof I hereto affix my signature.
